UNITED STATES PATENT OFFICE.

JAMES M. CONNER, OF GREENVILLE, NEW JERSEY.

DESIGN FOR FONT OF PRINTING-TYPES.

Specification forming part of Design No. **8,313**, dated May 4, 1875; application filed April 14, 1875.
[Term of Patent 7 years.]

To all whom it may concern:

Be it known that I, JAMES M. CONNER, of Greenville, Hudson county, New Jersey, have invented and produced a new and original Design for a Font of Printing-Type, of which the following is a specification:

The nature of my design is fully illustrated in the accompanying typographic impression, to which reference is made, and consists of an ornamented letter, as therein shown.

What I claim as new is—
The design for a font of printing-type, as shown.

JAMES M. CONNER.

In presence of—
WM. C. CONNER, Jr.,
WM. QUAIL.
